UNITED STATES PATENT OFFICE.

WILLIAM HUME LOGAN, OF LOUISVILLE, KENTUCKY, ASSIGNOR TO
KIRKER-BENDER FIRE ESCAPE COMPANY, OF LOUISVILLE, KEN-
TUCKY.

SPIRAL SLIDEWAY.

No. 818,383.

Specification of Letters Patent.

Patented April 17, 1906.

Application filed October 13, 1904. Serial No. 228,340.

To all whom it may concern:

Be it known that I, WILLIAM HUME LOGAN, a citizen of the United States, residing at Louisville, in the county of Jefferson and State of Kentucky, have invented certain new and useful Improvements in Spiral Slideways; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to amusement devices and package-chutes, and has for its object to provide a spirally-arranged slideway for pleasure seekers or packages to slide down.

20 A further object of my invention is to provide a device for these purposes which is particularly simple in its construction, easy to set up and knock down, safe, strong, and efficient.

25 With these objects in view my invention consists particularly in the novel spirally-arranged outside safety-guard.

My invention further consists in the novel central supporting means.

30 My invention further consists in certain other details of construction and in combination of parts, which will be first fully described and afterward specifically pointed out in the appended claims.

35 Referring to the accompanying drawings, Figure 1 is a perspective view of the slideway constructed in accordance with my invention. Fig. 2 is a horizontal cross-section taken on line 2-2 of Fig. 1. Fig. 3 is a fragmentary detail view of a part of slideway, vertical wall, safety-screen, and outer spiral screen. Fig. 4 is a fragmentary view showing a section of central stand-pipe and illustrating the slideway directly supported by the outer vertical supports, the vertical wall and safety-screen not being shown. Fig. 5 is a top plan of the construction shown in Fig. 4.

40 Like numerals of reference indicate the same parts throughout the several figures, in which—

45 1 indicates the spiral slideway, made of sections or flights 1' and suitably secured to a

stand-pipe 2, composed of sections 2', each of said sections having a core 3, Fig. 4, which 55 enters the section immediately above. By this construction the device may be compactly shipped and the parts rapidly assembled.

5 4 indicates the vertical wall, which follows 60 the spiral slideway, to which it is secured, said wall being for the purpose of providing a stiffening for the slideway, greatly strengthening the same and acting to hold the proper curve or contour in the slideway, which is 65 shown, Fig. 3, having its outer edge higher than its inner edge, said wall preferably not extending above the edge of the slideway.

10 In Fig. 1 I illustrate a series of outside vertical supports 5, preferably T-shaped in cross- 70 section, and supporting the slideway 1 by means of the braces or brackets 6. Resting

15 on said braces or brackets is a safety-screen 7, which follows the spiral slideway and fills the space between the same and vertical sup- 75 ports 5, which are at a distance and out of reach from the slideway, so that the passengers could not be injured by holding out their hands or arms during their descent, the safety-screen guarding against any one fall- 80

ing over the vertical wall 4. It will be no- 85 ticed that this safety-screen is made, prefer- ably, of a series of heavy wires or light iron rods 7', which are laid spirally upon the braces or brackets 6. This construction is 90

preferable to that of a small-mesh wire, for the reason that the interstices therein and the weave of the wire present a somewhat roughened surface, and would be injurious to the hands, arms, or garments of the passen- 95 gers, while in my present construction the safety-screen would offer little or no friction to any object in contact therewith. The outside spiral guard-wall 8 is constructed simi- 100 larly to the safety-screen, as shown, and this construction is much more preferable than a cylindrical cage or covering inclosing the entire tower, principally on account of the much lower cost of my present construction and on account of the improved appearance, 105 and also because it allows a better view of the slideway and its passengers. A suitable pas- sage 9 leads to the top of the slideway, and a suitable guard 10 is located at the bottom of

110 slideway to shield any derangement of dress 105 which might occur.

In Fig. 4 I illustrate a section 2' of the central stand-pipe 2, showing also section of slideway 1 secured thereto.

Having thus described the several parts of my invention, its operation is obvious. The passengers are conveyed by any suitable means to the passage at the top of the slideway, where their descent is started, and they slide down spirally, making their exit at the bottom of the slideway. This device is particularly adapted also to be used as a package-chute to be used in stores for conveying packages and bundles from one floor to another.

15 What I claim as my invention, and desire to secure by Letters Patent of the United States, is—

1. A spiral slideway having a central supporting means a safety-screen comprising a series of spirally-arranged wires, said safety-screen being on the outside of said slideway, and an outer spiral guard-wall comprising a series of spirally-arranged wires, substantially as described.

25 2. A spiral slideway having a central supporting means, a vertical stiffening-wall secured to said slideway, an outer guard-wall constructed of a series of spirally-arranged

wires, and a safety-screen interposed between the said slideway and the said outer guard-wall, said safety-screen being constructed of a series of spirally-arranged wires, substantially as described.

3. A spiral slideway having a dish or curve therein and having a central supporting means constructed in sections, a spirally-arranged vertical stiffening-wall secured to the outer edge of said slideway, the top edge of said wall extending only to the top edge of said slideway, whereby the dish or curve of the slideway is preserved regular and unbroken, substantially as described.

4. A spiral slideway having its central supporting means constructed in sections, a core in each of said sections arranged to enter its adjacent section, and a series of flights constructed independent of the central sectional supporting means and secured to the said sectional central supporting means, substantially as described.

In testimony whereof I affix my signature in presence of two witnesses.

WILLIAM HUME LOGAN.
